(57) **CLAIM**

The ornamental design for a combined fruit bowl and fruit tree, as shown and described.

DESCRIPTION

FIG. 1 is a perspective view of a combined fruit bowl and fruit tree showing our new design;

FIG. 2 is a top plan view thereof;

FIG. 3 is a fragmentary view, on an enlarged scale, of an alternative mesh material used to form the bottom wall denoted by the number 3 in FIG. 2;

FIG. 4 is a front elevational view thereof;

FIG. 5 is a side elevational view thereof; and,

FIG. 6 is a bottom plan view thereof.

The dotted-line showing in the drawings illustrates environmental matter and forms no part of the claimed design.
